UNITED STATES PATENT OFFICE.

EMANUEL AUFIERO, OF BROOKLYN, NEW YORK.

DESIGN FOR AN AUTOMOBILE-HORN.

42,928.

Specification for Design.

Patented Aug. 27, 1912.

Application filed June 5, 1912. Serial No. 701,906. Term of patent 7 years.

To all whom it may concern:

Be it known that I, EMANUEL AUFIERO, a citizen of the United States, residing at Brooklyn, in the county of Kings and State of New York, have invented a new, original, and ornamental Design for an Automobile-Horn, of which the following is a specification, reference being had to the accompanying drawing, forming a part thereof.

The figure shown is a side view of my new design.

I claim:

The ornamental design for an automobile horn as shown.

EMANUEL AUFIERO.

Witnesses:

ISAAC BROWN,
JULIUS F. HOERIG.
